COMBINED MINIATURE LAMP AND REFLECTOR THEREFOR

Robert G. Morgan, Ipswich, Mass., and Richard E. Smith,
Scotch Plains, N.J., assignors to Sylvania Electric Prod-
ucts Inc., a corporation of Delaware

Filed Oct. 23, 1965, Ser. No. 87,868

Term of patent 14 years

(Cl. D48—16)

FIG.1

FIG.2

FIG.3

FIG.4

FIG.5

FIGURE 1 is a perspective view of a combined miniature lamp and reflector therefor showing our new design.

FIGURE 2 is a front elevational view thereof.

FIGURE 3 is a side elevational view thereof.

FIGURE 4 is a rear elevational view thereof.

FIGURE 5 is an elevational view of the side thereof opposite that shown in FIGURE 3.

We claim:

The ornamental design for a combined miniature lamp and reflector therefor, as shown.
